UNITED STATES PATENT OFFICE.

RENÉ MERCIER, OF PARIS, FRANCE, ASSIGNOR TO COMPAGNIE CONTINENTALE POUR LA FABRICATION DES COMPTEURS & AUTRES APPAREILS, OF PARIS, FRANCE.

CASING FOR ELECTRIC METERS.

Application filed July 22, 1925, Serial No. 45,439, and in France November 7, 1924.

The casing for electric meters for subscribers, usually consists of a metallic envelope. Various metals such as iron, aluminum, zinc, brass, and the like, are employed for this purpose and said casings are manufactured in the most economical manner by the casting process or by stamping in a single piece. In order to protect the meter against the disturbing influence of the external fields, it has been the usual practice to construct the said casings exclusively of cast iron or sheet iron.

A very serious drawback which is observed in the use of such casings consists in the fact that it changes the standardizing of the meter which is always regulated in the laboratory with the casing removed by reason of the magnetic shunting produced by the metal of the casing upon the damping magnet which is always at a short distance therefrom.

The casing, the object of my invention, allows of preserving the advantages of the protection afforded by the magnetic casings either cast or stamped in one piece, which can be made at a small cost, and also of eliminating the difficulties in regulating which result from their use. For this purpose the wall of the casing is formed in the region near the magnet, of a non-magnetic metal such as copper, bronze, aluminum, etc., the said portion of the wall having suitable dimensions in order that the magnetic part of the casing shall no longer affect the magnet.

In the accompanying drawings,

Figs. 1 and 2 are side views illustrating somewhat diagrammatically, two embodiments of the present invention; and

Figs. 3 and 4 are detail sectional views illustrating two methods for securing a disk of non-magnetic metal to the casing in accordance with the present invention.

Referring to Figures 1 and 3, α designates a magnet adapted for the braking of the disk I of the meter, which disk is rotatable about its axis $x-x$.

In the front portion C of said casing and adjacent to the poles α_1 of the magnet α , is inserted a plate A of non-magnetic material, which plate may be of a circular shape; the purpose of said plate being to prevent the lines of force of the magnet (Fig. 3) being completed through the walls of said casing, which would occur if the casing were wholly of magnetic material.

The shape of the said plate may be chosen as desired; it may even have the shape of the front face of the said casing, i. e. it may cover the whole of the front face, as shown in Fig. 2 at B if the magnet is situated at the front, or it may have any suitable disposition, which may be favorable to the appearance of the apparatus.

The manner in which the plate is secured to the casing is optional; in particular, the plate may consist of a piece which may be riveted or soldered, or may be secured in place by means of a cast alloy, as illustrated in Fig. 3, or which may be secured in place by upsetting portions of the casing, as is shown in Fig. 4.

What I claim is:—

In an electric meter of the type described having a damping magnet, a casing of magnetic material for said meter, a cover of magnetic material for said casing and a metallic non-magnetic insert carried by said cover in the portion thereof lying within the magnetic field of said damping magnet for the purpose disclosed.

In testimony whereof I have signed this specification.

MERCIER, RENÉ.
